GAME APPARATUS

Herman Peterson, Ridgway, Colo.

Application April 15, 1941, Serial No. 388,668

1 Claim. (Cl. 273—120)

This invention relates to new and useful improvements in game apparatus and more particularly to a game apparatus which incorporates a number of interesting games and factors of popular interest.

The principal object of the present invention is to provide a game apparatus which includes a spinning member for throwing a ball or marble centrifugally, either into an annulus having various valued pockets or into certain receptors on the spinning member itself.

Various objects and advantages of the invention will become apparent to the reader of the following specification.

In the drawings:

Figure 1 is a top plan view of the game apparatus.

Figure 2 is a side elevation.

Figure 3 is a diametrical sectional view.

Figure 4 is a vertical sectional view taken substantially on the line 4—4 of Figure 1.

Referring to the drawings wherein like numerals designate like parts, it can be seen that numeral 5 denotes a base from which arises an annular side wall 6, at the inner side of which is an inclined ledge 7 marked into different valued areas by short partitions 8.

Within the confines of the ledge 7 is a shallow conical wheel 9 which has a bearing pin 10 depending from a holding structure 11 at the apex of the wheel 9. This pin 10 extends downwardly in a tube 12 rising from plates 13 and 14 on the base 5 and as shown in Figure 3, this bearing pin 10 is pointed at its lower end and rests on a bearing block 15.

Above the wheel 9 is a hopper 16 which is supported by a pair of leg members 17, 17 which extend downwardly through openings in the apex portion of the wheel 9. The hopper is readily removable at any time to permit the apparatus to be packed in a small compartment. On the hopper 16 is some ornament such as is denoted by numeral 18.

Suitably secured to the apex portion of the wheel 9 are V-shaped deflectors 19 arranged to provide avenues 20 through which a marble or ball will be required to roll after it has been dropped through the hopper 16.

Close to the periphery of the wheel 9 are arcuately shaped cleats 21, the ends of these cleats being in spaced relation. Between the ends of the cleats and still affording ample space through which a marble can pass to reach the ledge 7 are receptors 22, 23, 24 and 25, which may be referred to respectively as the "dog house" the

"treasurer house" the "lake" and the "jail." A marble can be removed from the lake 24 by inserting a finger from the top to reach the marble. However, it is preferable that the other structures 22, 23 and 25 be constructed on the order of what is shown in Figure 4 and which briefly is a box-like structure *a* having an entrance opening *b* for a marble and a hinged closure *c* at the rear side to permit ready removal of the trapped marble.

An annular rail 26 is mounted on legs 27 above the peripheral edge of the wheel 9 and, of course, is grasped and whirled when the wheel is to be spun.

Obviously, numerous games can be played on this game apparatus. The game can be played with cards or without cards and the wheel can be manufactured very cheaply from ply-board or some other similar inexpensive material. The various pockets and other fixtures may be of different colors to distinguish the same.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

30 In a game apparatus, a base, an annular member on said base forming a vertical wall and having an internal central ledge extending around the same in inwardly and upwardly inclined position and forming with the upper portion of 35 said member a circular trough spaced above said base, vertical partitions in said trough spaced around the same, a conical turntable rotatably mounted on said base within the confines of said ledge in edge-to-edge relation thereto and for 40 deflecting under rotation thereof small player pieces deposited thereon into said trough between the different partitions, a ball hopper mounted on the center of the table above the same for depositing player pieces on the table, a plurality of traps on said table spaced around the edge thereof for trapping player pieces before they reach the trough, and arcuate baffle cleats on said table intermediate contiguous traps, respectively, and having ends spaced from 45 the traps to permit the player pieces to escape between said traps and said cleats into said trough, said cleats being constructed and arranged to direct the player pieces toward the traps.

HERMAN PETERSON.
